UNITED STATES PATENT OFFICE

2,384,662

ANIMATED ILLUSTRATION

Julian R. Wehr, Roxbury, Vt.

Application May 30, 1945, Serial No. 596,662

7 Claims. (Cl. 46—36)

This invention relates to new and useful improvements in animated illustrations.

This application is an improvement on my application Serial No. 565,529, filed, November 29, 1944 for Animated illustrations.

The new and improved animated illustrations, in accordance with this invention, is characterized by a back sheet having its end portions passing through spaced openings in an illustrated front sheet so that said end portions overlie on the front sheet, and at least one of said end portions being connected with an illustrated piece disposed on the front sheet and which has a projecting portion engaging through another opening in the front sheet. With this arrangement it is possible to move the back sheet by moving its free projecting end portion, and thus will indirectly cause the illustrated front piece to be moved.

The invention also intends that the back sheet be associated with stem portions projecting from additional illustrated pieces disposed upon said front sheet and having said stem portions engaging through additional openings in the front sheet. With this arrangement the back sheet may be moved for moving all of the illustrated pieces on the front sheet. By utilizing one of the projecting end portions of the back sheet for moving the connected illustrated piece, it is possible to construct an animated illustration of greater interest.

The invention also proposes to so construct certain of the openings in the front sheet, so that the back sheet may be moved in a longitudinal path, or may be pivoted, or may be moved so as to be a compound pivotal and longitudinal movement. A modified form of the invention has also been disclosed, in this specification, in which a second illustrated piece which is also disposed upon the front sheet, is pivotally connected with the first named illustrated piece, and this second illustrated piece is provided with a projecting portion engaging through another opening in said front sheet, whereby it is possible to add additional movements and greater interest to the animated illustration.

The invention also proposes the construction of an improved animated illustration as briefly explained which may be manufactured at low cost so that it may be used as pages in an animated book.

For further comprehension of the invention and of the objects and advantages thereof, reference will be had to the following description and accompanying drawings, and to the appended

claims in which the various novel features of the invention are more particularly set forth.

In the accompanying drawing forming a material part of this disclosure:

5 Fig. 1 is a perspective view of a page of an animated book, constructed in accordance with this invention.

10 Fig. 2 is an elevational view of the page shown in Fig. 1 but with the parts in a different position.

15 Fig. 3 is an enlarged sectional view taken on the line 3—3 of Fig. 1 but turned around to a vertical position.

20 Fig. 4 is an elevational view of one of the illustrated pieces of the animation shown in Figs. 1 and 2.

Fig. 5 is an elevational view of another one of the pieces.

25 Fig. 6 is an elevational view of still another one of the pieces.

Fig. 7 is an end elevational view of the back sheet which is used in the animation.

30 Fig. 8 is an elevational view of another book page embodying a modified form of this invention.

Fig. 9 is an elevational view of the page shown in Fig. 8 but with the parts moved to another position.

35 Fig. 10 is a vertical sectional view substantially taken on the line 10—10 of Fig. 9.

Fig. 11 is an elevational view of one of the illustrated pieces used in Figs. 8 and 9.

Fig. 12 is an elevational view of still another one of the illustrated pieces.

35 Fig. 13 is an elevational view of still another illustrated piece.

Fig. 14 is an elevational view of still another of the illustrated pieces.

40 Fig. 15 is an elevational view of the back sheet used in Figs. 8 and 9.

The animated illustration, in accordance with that form of the invention illustrated in Figs. 1 to 7 inclusive, includes an illustrated front sheet 10 having a pair of spaced openings 11 and 12.

45 The opening 11 is elliptical and simulates the neck opening of the donkey illustrated on the sheet 10. The opening 12 is in the nature of an arcuate slit. A back sheet 14 has its end portions 15 and 16 passing through said spaced openings

50 11 and 12 and overlaying on said side front sheet 10. This back sheet 14 has one of its ends, namely the end portion 15 illustrated to fit into the illustration on the front sheet 10. The illustrated end portion 15 simulates the neck of the donkey.

55 The end portion 16 is in the nature of a tab by

which the animated illustration may be operated. The end portion 15 is slightly narrower than the height of the opening 11 so that the back sheet 14 is slidably supported. The slit 12 is much wider than the end portion 16 so that the back sheet 14 may be swung upwards and downwards using the opening 11 as a pivot.

An illustrated piece 18 is disposed upon the front sheet 10 and is pivotally connected with the illustrated end portion 15 of the back sheet 14. This illustrated piece 18 has a projecting portion 19 which engages through another opening or slit 20 in the front sheet 10. The slit 20 is slightly wider than the width of the projecting portion 19. The illustrated piece 18 is in the nature of the head of the donkey. The projecting portion 19 simulates flowers which the donkey is eating out from the flower pot which is part of the illustrated front sheet 10. The illustrated piece 18 has an opening 21 through which an eye 22 formed on the back sheet 14 is visible, so that when the animation is worked the eye of the donkey will move. The illustrated piece 18 has a headed lug 22' which engages through an opening 23 formed in the end portion 15 of the back sheet 14 and comprising a pivotal connection between the back sheet 14 and the illustrated piece 18. The end portion 15 of the back sheet 14 is also provided with a portion of the jaw 23' of the donkey which will move relative to the head 18 when the animation is worked.

The animation is also provided with additional illustrated pieces, namely the pieces 25 and 30. The piece 25 represents a monkey. It is provided with a projecting stem 26 which engages through a small opening 27 formed in the front sheet 10. This stem 26 also engages through an opening 28 formed in the back sheet 14. The stem 26 has an enlarged portion 29 immediately beneath the opening 27 which serves to pivotally support the piece 25.

The piece 30 is in the nature of the hind legs of the donkey. It is also provided with a projecting stem 31 which engages through an opening 32 formed in the front sheet 10. This stem 31 also passes through an opening 33 formed in the back sheet 14. The stem 31 is provided with an enlarged portion 34 below the opening 32 by which the hind legs 30 are pivotally supported on the front sheet 10.

The front sheet 10 is bent at one side 36 and continues into a back section 37 which extends across and covers the pieces on the back of the illustrated front sheet 10.

The dominating feature of this invention resides in the fact that the back sheet 14 has an end portion which extends out from an opening in the front sheet 10, and this extended end pivotally connects with and operates an illustrated piece.

In Figs. 8 to 15 inclusive, another form of the invention has been disclosed which is very similar to the prior form, but distinguishes in the fact that a second illustrated piece 40 is disposed upon the front sheet of the animation and pivotally connects with a first illustrated piece 41 which in turn is pivotally connected with a back sheet 42. The second illustrated piece 40 is also provided with a projecting portion 43 which engages through a slit 44 formed in the front sheet of the animation.

This second form of the invention may be better understood by noting that it includes an illustrated front sheet 45 having a pair

of spaced openings 46 and 47. The back sheet 42 has its end portions 48 and 49 passing through said spaced openings 46 and 47 and overlying on the front sheet 45. The projecting end portion 48 is slightly narrower than the slot 46 so that the slot 46 will guide the back sheet 42 in longitudinal sliding. The opening 47 is in the nature of an arcuate slit which is much wider than the projecting end portion 49 so that the back sheet 42 may be pivoted as well as moved longitudinally. The back sheet 42 has an enlarged central portion 59 the end shoulders of which act as stops against the ends of the openings 46 and 47, limiting movements of the back sheet 42.

The illustrated piece 41 is disposed upon the front sheet 45 and is provided with projecting headed lug 50 which engages through an opening 51 in the back sheet 42, by which the illustrated piece 41 is pivotally connected with the back sheet 42. The illustrated piece 41 is also provided with a projecting portion 53 which engages through another opening, or slit 54 formed in the front sheet 45. The second illustrated piece 40 is provided with an opening 55 through which the headed lug 50 passes and by which the second illustrated piece 40 is pivotally connected with the illustrated piece 41.

The animation also includes additional illustrated pieces 56 and 57. The piece 56 passes through an opening 58 formed in the front sheet 45. This latter portion of the piece 56 is in the nature of a stem portion 59 which is provided with a headed lug 60 engaging through an opening 61 in the back sheet 42. The lug 60 engaging the opening 61 serves to pivotally connect the illustrated piece 56 with the back sheet 42.

The piece 57 is provided with a stem portion 63 which passes through an opening 64 in the front sheet 45, and which also engages through an opening 65 in the back sheet 42. The stem portion 63 has an enlargement 66 immediately below the opening 64 by which the piece 57 is pivotally mounted on the front sheet 45.

The animation is operated by moving the end portion 49 of the back sheet 42. This end portion 49 may be pivoted upwards and downwards and may be moved right or left, or may be moved a component movement of these possible movements. When this is done the illustrated pieces will be moved. Figs. 8 and 9 show two different possible positions of the pieces. A page section 68 extends across the back of the front sheet 45.

The dominating feature of this form of the invention resides in the fact that the back sheet 42 has its end portions engaging through space openings 46 and 47 in the front sheet 45 and has one of its ends pivotally connected with a pair of illustrated pieces 40 and 41 which are pivotally connected with each other, and which are provided with projecting portions 43 and 53 engaging through slits 44 and 54 in the front sheet 45.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In an animated illustration, an illustrated front sheet having a pair of spaced openings, a back sheet having its end portions passing

through said openings and overlying said front sheet, and an illustrated piece on said front sheet and pivotally connected with one of said end portions and having a projecting portion engaging through another opening in said front sheet.

2. In an animated illustration, an illustrated front sheet having a pair of spaced opening, a back sheet having its end portions passing through said openings and overlying said front sheet, and an illustrated piece on said front sheet and pivotally connected with one of said end portions and having a projecting portion engaging through another opening in said front sheet, the pivotal connection between said illustrated piece and said back sheet comprising a headed lug on one of these parts engaging through an opening on the other of these parts.

3. In an animated illustration, an illustrated front sheet having a pair of spaced openings, a back sheet having its end portions passing through said openings and overlying said front sheet, and an illustrated piece on said front sheet and pivotally connected with one of said end portions and having a projecting portion engaging through another opening in said front sheet, one of said pair of spaced openings being slightly wider than that portion of the back sheet passing through it and the other of said pair of spaced openings being much wider than that portion of the back sheet passing through it, whereby said back sheet may be pivoted and moved longitudinally or moved in component motions of these movements.

4. In an animated illustration, an illustrated front sheet having a pair of spaced openings, a back sheet having its end portions passing through said openings and overlying said front sheet, and an illustrated piece on said front sheet and pivotally connected with one of said end portions and having a projecting portion engaging through another opening in said front sheet, said projecting portion being slightly narrower than the opening through which it passes so that the

illustrated piece will be pivotally moved when said back sheet is moved.

5. In an animated illustration, a front sheet having a pair of spaced openings, a back sheet having its end portions passing through said spaced openings and overlying said front sheet and at least one of said end portions being illustrated to fit into the illustration of said front sheet, and an illustrated piece on said front sheet and pivotally connected with said illustrated end portion and having a projecting portion engaging through another opening in said front sheet.

6. In an animated illustration, an illustrated front sheet having a pair of spaced openings, a back sheet having its end portions passing through said openings and overlying said front sheet, an illustrated piece on said front sheet and pivotally connected with one of said end portions and having a projecting portion engaging through another opening in said front sheet, a second illustrated piece on said front sheet and pivotally connected with said first named illustrated piece and having a projecting portion engaging through another opening in said front sheet.

7. In an animated illustration, an illustrated front sheet having a pair of spaced openings, a back sheet having its end portions passing through said openings and overlying said front sheet, an illustrated piece on said front sheet and pivotally connected with one of said end portions and having a projecting portion engaging through another opening in said front sheet, a second illustrated piece on said front sheet and pivotally connected with said first named illustrated piece and having a projecting portion engaging through another opening in said front sheet, said illustrated pieces being pivotally connected with said back sheet with a headed lug on one of the parts engaging through openings in the other of the parts.

JULIAN R. WEHR.
